AUTOMATIC RADIO DIRECTION FINDER

James W. Schwartz, Phoenix, Ariz., assignor, by mesne assignments, to Regency Electronics, Indianapolis, Ind.

Filed Sept. 26, 1961, Ser. No. 140,872

6 Claims. (Cl. 343—113)

This invention relates to radio direction finders and more specifically to improvements in a radio direction finder wherein signals of a directional antenna and isotropic antenna in quadrature to one another are added to produce a signal having unambiguous position information therein.

Radio direction finders using directional antenna are well known to the art. The directional antenna can, for example, be a loop antenna which is rotated such that the amplitude of the signal received by the antenna will vary from a maximum to a minimum during each 180° of rotation. The direction of the transmitting station can be determined from the maximum or minimum, but only after the inherent ambiguity is resolved. To resolve the ambiguity, it has been the practice to add to the signal from the directional antenna a second signal from an antenna which is non-directional. For instance, if the directional antenna is of the type which responds to the magnetic component of an electromagnetic wave being transmitted, a non-directional antenna of the type which responds to the electric field component of the wave may be provided and the signals from both added. Since the electric and magnetic vectors are in time quadrature to one another, the phase of the electric vector received may be shifted 90° by passive elements so that it will either add to or subtract from the signal received by the directional antenna depending upon the position of the directional antenna relative to the transmitting station. In that manner only one maximum and one minimum signal receiving position of the rotating directional antenna is simulated for its complete rotation through 360° to resolve the ambiguity.

The effect of the addition of the signals from the two antennae is to cancel one of the minima present in the signal from the directional antenna so that the net signal has only a single minimum or null. The practice has been to detect the null and thereby determine the null signal receiving position of the directional antenna to obtain relative bearing to the transmitting station. A typical radio-direction-finding system is described in a United States Patent 2,232,096 which provides a means for detecting a single null and another means responsive to the null detecting means for firing a thyratron which provides an electrical pulse that is employed to cause an appropriate visual representation of the position of the directional antenna relative to the transmitting station at that time, thereby providing a relative bearing to the transmitting station. The connection of the isotropic antenna in such systems will shift the null position of directional antenna. That is, the out of phase components measured by the ambiguity-resolving antenna will have components therein which are not at 90° with respect to the signal delivered by the directional antenna. Secondly, the precise position of the null point depends in part upon the relative magnitudes of the signals taken from the directional antenna and the non-directional antenna. Thus, a further null position inaccuracy is placed in the system. Furthermore, since the prior systems are null-seeking systems, they must seek the absence of a signal. Accordingly, noise will interfere with the operation of the system.

The principle of the present invention is to base the measurement of the ambiguity-resolved signal on the phase of the envelope of the unambiguous signal. That

2

is to say, where the directional antenna is rotated at 1500 r.p.m., for example, the output wave shape will have a 25 cycle modulation. This will be the fundamental component of the envelope wave shape. The phase relationship of this envelope changes proportionally with a change in direction between the measuring antenna and the transmitting station to be detected.

The phase of the 25 cycle component of this signal is independent of the relative proportion of sense antenna signals and directional antenna signals and also is independent of the out of quadrature components injected into the system by the sense or ambiguity-resolving antenna. Furthermore, since it is now a phase relationship that is to be determined, noise will have much less influence on the measurement than it would in the case of a null-seeking system since the system of the present invention integrates over such disturbances.

In one embodiment of the invention, the envelope of the fundamental component of the received signal is appropriately selected as in a low frequency band pass filter. The signal is then clipped to produce a square wave which is thereafter passed through a differentiating circuit to produce a series of pulses. The series of pulses then pass through a second clipping stage whereby the remaining pulses are those generated at a time related to the phase of the signal. As the phase of this fundamental shifts due to a shift in the relative position between the measuring antenna and the transmitting station, the phase relationship of the pulses will shift proportionally.

These pulses can then be used to trigger any appropriate type of visual display means which will, for example, display a light on a pelorus scale calibrated in terms of direction. For example, the pulse can trigger a neon tube which is scanned by a rotating disc having an aperture therein where the disc rotates at the effective speed of rotation of the directional antenna system. Thus a pulse of light will be synchronously presented through the aperture each time the aperture passes the position corresponding to the direction of the transmitting station to be detected.

In a second and preferred embodiment, a harmonic component at twice the fundamental frequency is utilized to derive a series of pulses. The fundamental frequency component is then employed to enable only those pulses of a selected polarity generated at a time related to the phase of the signal to trigger the display means.

Accordingly, a primary object of this invention is to provide a novel radio direction finding system having improved accuracy.

Another object of this invention is to provide a novel radio direction finding signal which does not require the use of null detecting techniques.

A further object of this invention is to provide a novel radio direction system which is substantially independent of noise.

A further object of this invention is to provide a novel radio direction finding system which is unaffected by the out of quadrature component in an ambiguity-resolving antenna signal.

A further and important feature of the invention is to provide a novel radio direction finder system which responds to the phase of the fundamental frequency of the envelope of a detected signal.

These and other objects of the invention will be apparent from the following description when taken in connection with the drawings in which:

FIGURE 1 is a schematic block diagram of a first embodiment of the present invention.

FIGURE 2 shows a modification of the first embodiment of the invention wherein an actual rotating antenna

is utilized as contrasted to the simulated rotation for the directional antenna of FIGURE 1.

FIGURE 3 illustrates a second embodiment of the invention wherein the fundamental signal and a harmonic function thereof are used in performing the direction measurement.

FIGURE 4 shows the signal amplitude pattern of the directional antenna system of the embodiments of FIGURES 1, 2 and 3.

FIGURE 5 illustrates the antenna signal output of the directional antenna as a function of direction for any of the directional antenna of the embodiments of the invention illustrated in FIGURES 1 to 3.

FIGURE 6 illustrates the signal amplitude pattern after the addition of a signal from the ambiguity-resolving antenna for any of FIGURES 1 through 3.

FIGURE 7 illustrates the net antenna signal voltage as a function of the direction in which the directional antenna points after the ambiguity-resolving antenna signal is connected to the ambiguous directional signal.

FIGURE 8a illustrates the antenna voltage of the directional antenna as a function of direction.

FIGURE 8b illustrates on the same direction scale as FIGURE 8a the antenna voltage due to the ambiguity resolving antenna.

FIGURE 8c illustrates on the same direction scale as FIGURES 8a and 8b the antenna voltage after the addition between the two antenna signals of FIGURES 8a and 8b to illustrate the manner in which a single null is provided when the peak signal voltages of the two antenna being equal.

FIGURE 9 is similar to FIGURE 8c and illustrates the total voltage signal when the peak antenna voltage of the ambiguity-resolving antenna is larger than the peak voltage of the directional antenna.

FIGURE 10 is similar to FIGURES 8c and 9 but illustrates the total voltage when the peak voltage of the ambiguity-resolving antenna is less than the peak voltage of the directional antenna.

FIGURES 11a, 11b and 11c respectively illustrate voltage signal amplitude as a function of direction for the fundamental component of the envelope of the signals of 8c, 9 and 10, respectively, and specifically illustrate the manner in which the phase relationship of any of the signals of FIGURES 11a, 11b and 11c are identical to one another regardless of the proportion of the signal amplitudes between the directional antenna and ambiguity-resolving antenna.

FIGURE 12a illustrates the manner in which the fundamental wave shape of FIGURES 11a, 11b or 11c is clipped in a first clipper.

FIGURE 12b is plotted on the same directional scale as FIGURE 12a and illustrates the signal after it has been taken through a differentiator.

Referring now to FIGURE 1, two ferrite antennas 20 and 21 at right angles to one another are connected to an antenna rotation simulator 22 which is driven by a synchronous motor 23. The combination of directional antennas 20 and 21 and antenna rotation simulator 22 which is driven by motor 23 can be shown to be fully equivalent to a rotating directional antenna in that either will generate a signal pattern of the type illustrated generally in FIGURE 4. The signal amplitude pattern of FIGURE 4 can also be illustrated as the envelope of the received signal voltage plotted against direction in degrees as shown in FIGURE 5.

From FIGURES 4 and 5 it is seen that the signal received by the directional antenna system including antennas 20 and 21 is ambiguous since it will indicate null when the antenna system is directly pointed toward the station or directly pointed away from the station (zero and 180° respectively). In order to resolve this ambiguity, an isotropic antenna 24 has its signal connected into the system. Thus, the output signal of the directional

antenna and the signal of antenna 24 are combined in a phase shifter and mixer 25.

The signal delivered from simulator 22 is responsive to the magnetic field vector component of the electromagnetic wave received, while the signal received from antenna 24 is responsive to the electric field vector. These antenna voltages produced by these two fields are displaced 90° with respect to one another so that by phase shifting the signal due to the electric field vector of antenna 24 with respect to the signal due to the magnetic field vector of the directional antenna, one will be able to tell from which direction the radiation came.

Therefore, by phase shifting the output signal of antenna 24 (due to the electric field) by 90°, and adding it to the ambiguous directional signal from simulator 22, the antenna instantaneous voltages will be in opposition when the directional antenna points generally toward the transmitting station, but will be additive when the directional antenna points in a direction directly generally away from the transmitting station. Therefore, a null will be produced, only when the directional antenna points toward the transmitting station.

The signal amplitude pattern of the signal coming from phase shifter 25 is typically shown for example in FIGURE 6 with the envelope of the received signal being shown in FIGURE 7. From FIGURE 7 it is seen that the total signal has only a single null in the direction of the transmitting station.

The manner in which the single null of FIGURE 7 is produced can be seen from FIGURES 8a, 8b and 8c in each of which voltage signals involved are plotted as a function of the direction of the antenna system. In FIGURE 8a there is essentially a reproduction of the original signal shown in FIGURE 5 received by antennae 20 and 21 and modulated before combining in order to imitate the action of a rotating loop by the antenna rotation simulator 22. Note that in FIGURE 8a, at the left of the diagram there is an H to indicate that the voltage generated in this antenna system is due to the magnetic field component of the electromagnetic wave. In FIGURE 8b the voltage output of isotropic antenna 24 is shown as a function of direction where it is clear that the antenna voltage will be constant regardless of the direction of the radio station. FIGURE 8b has been labeled E' rather than E to indicate that the voltage from the isotropic antenna 24 has been phase shifted by 90°. Upon their addition or mixing in mixer 25, the net output voltage will be that of FIGURE 8c having only a single null.

As previously indicated, the attempts of the prior art have been to detect the position of this null, for example, by firing a thyratron tube which uses the envelope of FIGURE 7 as a biasing signal whereby the tube fires only at minimum input voltage conditions. The pulse generated by the firing of the tube can thereafter be used to trigger, for example, a neon glow tube which is shielded by a rotating scanning disc which has an aperture therein. The disc is rotated in synchronism with the effective rotational frequency of the antenna system including antennas 20 and 21 whereby the aperture in the disc casts a spot of light on a pelorus scale when there is a flash of the neon glow tube.

The sensing of the null is attendant with several disadvantages. For example, one major disadvantage is that upon connecting the sense antenna 24, the null position will move somewhat. Thus there is an inherent inaccuracy in the system even if the null could be exactly located by the measuring equipment. Furthermore, the exact position of the null can be obscured by noise throughout the system.

Also, the actual null may be poorly defined, depending upon the relative amplitude of the signal from the directional antenna and the isotropic antenna. Thus, in FIGURE 9 it is assumed that the voltage of the isotropic antenna is greater than that from the directional antenna

with the result that there is a poorly defined null. This problem will be overcome by the present invention. Again, in FIGURE 10 it is assumed that the voltage from the isotropic or ambiguity-resolving antenna is much less than the signal received by the directional antenna, with the result that two minima are now produced in each cycle. Thus, it is seen that the null seeking equipments of the prior art are dependent in part on the relative proportion of signal magnitudes from the two antenna systems.

In accordance with the present invention, the attempt to actually measure a null position is abandoned, it being recognized that the envelope of the antenna voltage will shift in phase as the direction of the transmitting station changes with respect to the equipment. Accordingly, the envelope of the received signal is operated upon to identify the unambiguous direction of the transmitting station. Thereafter, as shown in FIGURE 1, the unambiguous signal from the phase shifter and mixer 25 is applied to a band pass filter 26 which is tuned to the frequency of the fundamental of the envelope of the unambiguous signal. If the motor 23 drives the antenna-rotation simulator 22 at 1500 revolutions per minute, for example, the narrow pass filter will be tuned to only receive the 25 cycle modulation introduced by the simulated rotating loop antenna.

The wave shape of this resultant signal is shown in FIGURES 11a, 11b and 11c for the conditions of FIGURES 8c, 9 and 10, respectively. From a comparison of the three signals for the three different conditions shown it may be clearly seen that the phase of each of the signals is identical to one another regardless of any shift in null position or any difficulty in sensing a poorly defined null position. The signal from filter 26 is thereafter taken to a clipper 27 such as an over driven amplifier with cut-off limiting. The output of clipper 27 is the square wave shown in FIGURE 12a which is applied to a differentiator 28. The differentiator 28 delivers sharp pulses as illustrated in FIGURE 12b corresponding to the leading and trailing edges of the input square wave. By passing the 40 output of differentiator 28 through a second clipper 29 all but selected positive (or negative) pulses are eliminated at the output of clipping stage 29, the remaining pulses corresponding to the direction of the transmitting station, as scanning through 360° is operated continuously.

This pulse is then applied to an indicating device such as a neon tube 30 which is positioned behind a disc 31 that is rotated by the motor 23 in synchronism with the modulation frequency of the directional antenna signal. The disc 31 has an aperture 32 therein which rotates with respect to a transparent pelorus scale 33. Therefore, when the rotation simulator 22 produces a signal simulating a signal from a directional antenna aligned with the transmitting station, the neon tube 30 will produce a flash observable through the aperture 32 on the pelorus scale 33. The flash will occur in the illustrated embodiment 25 times per second which is well within the retentivity of the eye whereby a steady dot of light is observed.

It should be noted that a continuous non-ambiguous signal is provided by the present invention, while in null-seeking devices it is the practice to permit the ambiguous directional signal to be continuously presented (since sharp nulls are existent in such signals), and to switch in the ambiguity-resolving antenna only when sense is to be determined. In the present invention reliance is not placed on the null position so that the sense antenna can be constantly connected in the system without affecting it.

It should be further noted with reference to FIGURE 1 that a receiver 34 can be connected to the mixer 25 and that the receiver could, for example, be a superheterodyne system connected to a speaker 35 so that a transmitting station being tracked can be identified.

As noted hereinbefore, the antenna system including di-

rectional antennas 20 and 21 of FIGURE 1 could be replaced by and are the full equivalent of the actual rotating loop antenna. Thus, in FIGURE 2 a loop antenna 36 is illustrated which is directly rotated by a synchronous motor 37 which rotates, for example, at 25 revolutions per second and drives a scanning disc 38 which is similar to scanning disc 31 of FIGURE 1. In FIGURE 2, the signal measured by an antenna 24 is phase shifted in a phase shifter 39 and the two signals are thereafter added and directly connected to the superheterodyne receiver 40 where the signals are amplified. From the output of the last IF stage in the superheterodyne receiver 40 the amplified signal can be connected to the 25 cycle band pass filter and clipper combined schematically and represented by block 41. The advantage of this arrangement is utilization of the RF and IF amplification stages in the receiver to provide preamplification which would otherwise be required in the clipper 27 except for very strong signals received from a nearby station. The output square wave signal is then applied to the differentiator comprised of capacitor 42 and resistor 43 and the clipper, diode 28. Thus, a unidirectional pulse train is applied to the neon bulb 30 which cooperates with the scanning disc 38.

A preferred embodiment of the invention is best illustrated in FIGURE 3 wherein two frequency components of the received signal envelope are used with a received signal of the type shown in FIGURE 10. A signal envelope of that type is assured by mixing only one fourth of the signal amplitude from the isotropic antenna 24 with the signal from the antenna rotation simulator 22. A first band pass filter 52 passes the fundamental 25 cycle per second component of the modulated signal while the second band pass filter 50 passes the first harmonic frequency of the modulated signal. When too great a portion of the signal from the isotropic antenna is added in the signal there may be a flickering of the indication and some dispersion of the envelope wave shape. In accordance with the preferred embodiment of FIGURE 3, and assuming that a motor 23 causes a 25 cycle per second modulation of the directional signal, by adding a relatively small proportion of the isotropic signal, a 50 cycle harmonic frequency is produced as illustrated in FIGURE 10 at the output of phase shift mixer 25. This 50 cycle signal is passed by the sharply tuned band pass filter 50 and is applied to a limiter and differentiator 51 in much the same manner as in the system illustrated in FIGURE 1 whereby a 50 cycle pulse train is obtained.

A second channel is then provided which includes the band pass filter 52 tuned to the 25 cycle fundamental signal. This signal is applied to the biasing means of amplifier 53 which receives the output of limiter and differentiator means 51 whereby a pulse signal will be passed and amplified by amplifier 53 only during the positive half wave of the sinusoidal biasing voltage from the 25 cycle band pass filter 52. Accordingly, a strong positive pulse will be delivered from gated amplifier 53 at a frequency of 25 cycles to operate the indicating device. The system of FIGURE 3 will be operable even when weak signals are received and when only a small amount of the isotropic antenna signal is utilized.

In the foregoing, I have described my invention only in connection with preferred embodiments thereof. Many variations and modifications of the principles of my invention within the scope of the description herein are obvious. Accordingly, I prefer to be bound not by the specific disclosure herein, but only by the appended claims.

I claim:

1. A radio direction finder comprising directional antenna means for modulating a radio signal in accordance with the direction from which the radio signal comes and phase detecting means connected to said directional antenna means for measuring the phase of the envelope of said modulated signal, the indicator means connected to said phase detecting means; said indicator means being

operable to indicate direction as determined by the phase of said envelope of said radio signal; said phase detecting means including a first low frequency band pass filter for accepting only the fundamental frequency of said envelope and a second band pass frequency filter for accepting only a harmonic of said fundamental frequency; a pulse circuit means, said second band pass filter being connected to said pulse circuit means for generating voltage pulses at phases related to the phase of said harmonic of said fundamental frequency; a gated means; said second band pass filter being connected to said gated means; said gated means being connected to said indicator means; said gated means being connected to said first band pass filter and being abled only when said first band pass filter has a predetermined output.

2. A radio direction finder comprising directional antenna means for modulating a radio signal in accordance with the direction from which the radio signal comes and phase detecting means connected to said directional antenna means for measuring the phase of the envelope of said modulated signal with respect to a predetermined value; said phase detecting means including a first band pass filter for accepting only the fundamental frequency of said envelope and a second band pass frequency filter for accepting only a harmonic of said fundamental frequency; a pulse circuit means; said second band pass filter being connected to said pulse circuit means for generating voltage pulses at phases related to the phase of said harmonic of said fundamental frequency; a gated means; said second band pass filter being connected to said gated means; an indicator means; said gated means being connected to said indicator means; said gated means being connected to said first band pass filter and being abled only when said first band pass filter has a predetermined output.

3. In a direction finder; directional antenna means having a modulated output voltage containing a null value corresponding to the direction of a source of radio signals and measuring means for measuring the direction of said directional antenna corresponding to said null value; a first band pass filter for accepting only the fundamental frequency of said modulated output voltage and a second band pass frequency filter for accepting only a harmonic of said fundamental frequency; a pulse circuit means; said second band pass filter being connected to said pulse circuit means for generating voltage pulses at phases related to the phase of said harmonic of said fundamental frequency; a gated means; said second band pass filter being connected to said gated means; an indicator means; said gated means being connected to said indicator means; said gated means being connected to said first band pass filter and being abled only when said first band pass filter has a predetermined output; said measuring means including said first band pass filter for passing said fundamental frequency component of said modulated output voltage and pulse generating means for generating a pulse having a fixed phase relation with respect to said fundamental frequency component; and an indicating means; said indicating means being connected to said pulse generating means and indicating the direction of said source of radio signals corresponding to the position of said pulse.

4. In a direction finder; directional antenna means having a modulated output voltage containing a null value corresponding to the direction of a source of radio signals and measuring means for measuring the direction of said directional antenna corresponding to said null value; a first band pass filter for accepting only the fundamental frequency of said modulated output voltage and a second band pass frequency filter for accepting only a har-

monic of said fundamental frequency; a pulse circuit means; said second band pass filter being connected to said pulse circuit means for generating voltage pulses at phases related to the phase of said harmonic of said fundamental frequency; a gated means; said second band pass filter being connected to said gated means; an indicator means; said gated means being connected to said indicator means; said gated means being connected to said first band pass filter and being abled only when said first band pass filter has a predetermined output; said measuring means including said first band pass filter for passing the fundamental frequency component of said modulated output voltage and pulse generating means for generating a pulse having a fixed phase relation with respect to said fundamental component; and an indicating means; said indicating means being connected to said pulse generating means and indicating the direction of said source of radio signals corresponding to the position of said pulse; said directional antenna means including an isotropic antenna for eliminating direction ambiguity.

5. In a direction finder; directional antenna means having a modulated output voltage containing a null value corresponding to the direction of a source of radio signals and measuring means for measuring the direction of said directional antenna corresponding to said null value; said measuring means including a band pass filter for passing one component of said modulated output voltage and pulse generating means for generating a pulse having a fixed phase relation with respect to said one component; and an indicating means; said indicating means being connected to said pulse generating means and indicating the direction of said source of radio signals corresponding to the position of said pulse; said one component comprising the first harmonic component of said modulated output voltage; said pulse generating means including a second band pass filter for passing the fundamental component of said modulated output voltage; said pulse generating means including gated amplifier means controlled by said fundamental component of said modulated output voltage.

6. A radio direction finder comprising directional antenna means for modulating a radio signal in accordance with the direction from which the radio signal comes and phase detecting means connected to said directional antenna means for measuring the phase of the envelope of said modulated signal, and indicator means connected to said phase detecting means; said indicator means being operable to indicate direction as determined by the phase of said envelope of said radio signal; said phase detecting means including a first low frequency band pass filter for accepting only the fundamental frequency of said envelope and a second band pass frequency filter for accepting only a harmonic of said fundamental frequency; a pulse circuit means; said second band pass filter being connected to said pulse circuit means for generating voltage pulses at phases related to the phase of said harmonic of said fundamental frequency; a gated means; said second band pass filter being connected to said gated means; an indicator means; said gated means being connected to said indicator means; said gated means being connected to said first band pass filter and being operable between one of an abled or disabled position to the other of said abled or disabled position when said first band pass filter has a predetermined output.
